(57) **CLAIM**

I claim the ornamental design for a bicycle frame with cantilevered seat post, as shown and described.

DESCRIPTION

FIG. 1 is a top and left side perspective view of a bicycle frame with cantilevered seat post showing my new design; FIG. 2 is a bottom and right side perspective view of a bicycle frame with cantilevered seat post showing my new design;

FIG. 3 is a top, rear and left side perspective view of a bicycle frame with cantilevered seat post showing my new design;

FIG. 4 is a top, rear and right side perspective view of a bicycle frame with cantilevered seat post showing my new design;

FIG. 5 is a front and right side perspective view of a bicycle frame with cantilevered seat post showing my new design; FIG. 6 is a front and left side perspective view of a bicycle frame with cantilevered seat post showing my new design; FIG. 7 is a left side elevation view of the bicycle frame with cantilevered seat post of FIG. 1;

FIG. 8 is a right side elevation view of the bicycle frame with cantilevered seat post of FIG. 1;

FIG. 9 is a front elevation view of the bicycle frame with cantilevered seat post of FIG. 1;

FIG. 10 is a rear elevation view of the bicycle frame with cantilevered seat post of FIG. 1;

FIG. 11 is a top plan view of the bicycle frame with cantilevered seat post of FIG. 1; and,

FIG. 12 is a bottom plan view of the bicycle frame with cantilevered seat post of FIG. 1.
